RAIL BOND OR THE LIKE

Rolf Selquist, McKeesport, Pa., assignor to Cop-
perweld Steel Company, Glassport, Pa., a cor-
poration of Pennsylvania

Application April 3, 1944, Serial No. 529,295

2 Claims. (Cl. 287—20.3)

1

This invention relates to electrical connectors, such as rail bonds, and a method for their manufacture.

One type of rail bond or electrical connector which has been extensively used comprises a suitable length of conductor, usually a stranded cable of appropriate size, welded to one or more plugs having tapered shanks and adapted to be driven into holes drilled in the webs of railroad rails. Annealed wire has been used heretofore for the conductor because of the necessity for bending the conductor which is shipped straight, to the desired curvature adjacent the ends when installing it in the field. The necessity for manually shaping the conductor has prevented the use of hard-drawn wire, even though it is stronger than annealed wire, in making a bond of the conventional welded type. Bonds of this type have in certain cases exhibited fatigue failure of the conductor adjacent the head of the plug. It will be appreciated that, under the conditions of service existing on railroads carrying heavy traffic, rail bonds are repeatedly subjected to severe vibration and impact so that the resistance of a bond to failure by fatigue is one of its most important qualities.

The object of my invention is to provide a rail bond or the like having a conductor of hard-drawn wire throughout and therefore characterized by a greater fatigue strength than the bonds including conductors of annealed wire welded to drive plugs. In a preferred embodiment, my improved bond comprises a suitable length of conductor, preferably stranded, composed of hard-drawn wire, inserted through a transverse hole in the head of a drive plug, the conductor being secured to the plug substantially exclusively by the frictional grip of the latter on the former.

A complete understanding of my novel bond and method of manufacture may be obtained from the following detailed description which refers to the accompanying drawings illustrating a preferred embodiment and practice. In the drawings,

Figure 1 is an elevation of a drive plug adapted to receive a conductor to form a bond according to my invention;

Figure 2 is a similar view taken at right angles to Figure 1;

Figure 3 is a partial section through a deforming apparatus adapted to operate on a plug having a conductor inserted therethrough;

Figure 4 is a partial elevation of a bond after completion of the head-deforming operation;

2

Figure 5 is an elevation to enlarged scale of the bond taken at right angles to Figure 4;

Figure 6 is a partial section also to enlarged scale taken along the plane of line VI—VI of Figure 4; and

Figure 7 is a set of curves showing graphically the performance of my bond under fatigue test, as compared with bonds having conductors welded to the drive plug.

10 The improved bond of my invention may best be understood from a description of the method by which it is manufactured. In the preferred method, I provide a drive plug 10 having a head 11 and a tapered shank 12. The top of the head 11 may conveniently have the form of a spherical segment as indicated at 13. A transverse hole 14 is drilled through the head on a diameter thereof and is countersunk as at 15.

To attach a conductor to the plug 10, I insert 20 a length of suitable conductor 16 of hard-drawn wire, free from the softening resulting from annealing, preferably a stranded cable, through the hole 14 until the end of the cable is substantially flush with the end of the hole opposite 25 the countersink 15. As shown in Figure 4, the size of the hole 14 is such as to provide slight clearance for the conductor to facilitate insertion of the latter. When the conductor has been inserted in the hole through the head of the plug, I 30 subject the head to a deforming operation whereby the head is caused to obtain a tight frictional grip on the conductor. This operation may conveniently be effected by apparatus such as that indicated diagrammatically in Figure 3, including 35 a die plate 17 resting on a base plate 18 which may be the platen of a press having a reciprocable head 19. The die plate 17 has a tapered bore 20 therein adapted to accommodate the shank 12 of the plug in axial alignment with 40 the head 19.

When the die head 19 of the press is caused to descend with sufficient force, the head 11 is deformed by compression or squeezing so that it obtains a tight frictional grip on the conductor.

45 The hole 14 is somewhat contracted and the conductor itself, if stranded, is slightly compacted. If the die head 19 is plane on the end, the spherically shaped top 13 of the head 11 is flattened as indicated at 21 in Figure 4 which shows one 50 end of a completed bond, the other end being identical. If it is desired that the heads of the plugs retain a rounded top after deformation, the die head 19 may be made concave at its end.

Figures 5 and 6 further show the finished bond. 55 The end of the conductor is slightly flattened

as a result of the crushing down of the plug head under the force of the press, as shown in Figure 5. The interior of the hole 14 is slightly indented by the strands of the conductor, as shown in Figure 6, if the head of the plug is sufficiently deformed. This is desirable since it improves the frictional grip of the head on the conductor, lessening the chance that the conductor will be pulled out of the hole in service. The countersink 15 is an important feature in that it eliminates the sharp edge of the hole which might otherwise nick or notch the strands of the conductor under severe vibration in service, which would reduce the fatigue resistance of the bond. It also prevents the application of compressive stress to the conductor where it leaves the head, which would otherwise result in a region of localized stress concentration further tending to reduce the fatigue resistance.

Figure 7 shows graphically the comparison between my improved bond and the welded bond under fatigue test. In this test, samples were subjected to repeated bending of the conductor in opposite directions through small angles while the plug was held firmly fixed. Curve A is drawn through the experimental points designated by dots, obtained in tests of welded bonds. Curve B is drawn through experimental points indicated by circles, obtained from tests on the bond of my invention. It will be readily apparent that my bond exhibits considerably higher endurance under fatigue test than the welded bond. That is to say, for the same angle of bend, my bond withstood a great many more repeated cycles of bending than the welded bond or, for the same number of bends, my bond could be bent through a considerably greater angle than the welded bond. This increased endurance results from the use of hard-drawn wire for the conductor and a method of attaching it to the plugs which does not involve heating the wire to a temperature above the critical point, leaving the wire in its original hard-drawn state throughout.

My invention is also characterized by further advantages. In the first place, the cost is lower than that of the welded bond since the deformation of the head of the drive plug is a less expensive operation than the welding of the conductor to the head. My bond has a total resistance substantially the same as that of the welded bond. My bond is also characterized by ample resistance to pulling out of the conductor from

the plug. A further advantage is that my improved bond may be applied to the rail in exactly the same manner as the bonds previously used.

It will be apparent that, while the invention has been described with particular reference to bonds, it is also useful in connectors which have a drive plug at one end only of the conductor.

Although I have illustrated and described but a preferred embodiment and practice of my invention, it will be understood that changes in the design of the parts or in the manufacturing procedure may be made without departing from the spirit of the invention or the scope of the appended claims.

I claim:

1. A rail bond comprising a pair of drive plugs and a length of conductor, said conductor being composed of hard-drawn wire and having its ends extending into said plugs, respectively, and secured therein by a frictional grip, whereby the conductor is left in its original hard-drawn state and remains free from the softening resulting from annealing, at least in the portions thereof adjacent the plugs, and is therefore more resistant to fatigue failure under the repeated vibration to which it is subjected in service than a bond having a conductor which has been annealed at the points of connection to the plugs.

2. A rail bond comprising a length of conductor with a drive plug at each end thereof, the ends of the conductor extending into holes in the plugs, respectively, and secured therein by a frictional grip, said holes being countersunk at the ends into which the conductor extends, thereby preventing localized stress concentrations at the points where the conductor enters the plugs.

ROLF SELQUIST.
